UNITED STATES PATENT OFFICE.

JOHN HOTHAM, OF HILLSIDE, PENNSYLVANIA.

KNOCKDOWN BOX.

SPECIFICATION forming part of Letters Patent No. 371,322, dated October 11, 1887.

Application filed May 3, 1887. Serial No. 236,959. (No model.)

To all whom it may concern:

Be it known that I, JOHN HOTHAM, of Hill-side, in the county of Westmoreland and State of Pennsylvania, have invented a new and Improved Knockdown Box, of which the following is a full, clear, and exact description.

Reference is to be had to the accompanying drawings, forming a part of this specification, in which similar letters of reference indicate corresponding parts in all the figures.

Figure 1 is a perspective view of my new and improved knockdown box as it appears when set up and closed. Fig. 2 is a central longitudinal sectional elevation. Fig. 3 is a transverse sectional elevation taken on the line $x x$ of Fig. 2, and Fig. 4 is an end view of the body of the box folded.

The invention will first be described in connection with the drawings, and then pointed out in the claims.

The body of the box is composed of the two side pieces, $a a$, duplicates of each other, and the two end pieces, $b b$. The side pieces, $a a$, are united at their ends to the edges of the end pieces by the hinges $c c$, which permit the body of the box to fold into substantially a flat state, as shown in Fig. 4, and also enable it to be easily and quickly set up into box form, as shown in Fig. 1. The upper and lower edges of the side pieces, a , are turned or partially rolled to form the flanges a' , with which the flanges $d d'$ of the top and bottom pieces, $D D'$, engage to form secure clasps or joints, as shown clearly in Fig. 3.

The end piece, b , of the box is formed at its upper and lower edges with the inwardly-projecting flanges $h h$, to support the plain ends of the top and bottom pieces, $D D'$, as shown in Fig. 2, and so that there will be no spaces between the said end piece and the adjacent ends of the top and bottom pieces. The opposite end piece, b' , is made plain at its upper and lower edges, and is provided near its upper edge with two fastening-lugs, f , which project outward.

The cover D is formed with a flange, d^2 , in which the small slots or openings d^3 are cut to receive the fastening-lugs f when the cover is put in place, as shown in Fig. 2. The lugs f are perforated to receive the fastening-pins e^3 for fastening the cover upon the box. The pins e^3 are made in this instance a part of the spring-

arms e' , held to the outer surface of the end wall, b' , by the clasp e^2 , so that the fastening device for the cover becomes a permanent part of the box and is always at hand.

The bottom piece, D' , of the box is formed with the flange g , provided with the inwardly-projecting studs $g' g'$, which are adapted to pass through small openings or slots g^2 , made near the lower edge of the end wall b' , as shown in Fig. 2. The studs g' are perforated to receive fastening-pins g^3 for locking the bottom piece, D' , to the main body of the box. The pins g^3 are made a part of the spring-arms g^4 , held to the inner surface of the end wall, b' , by the clasp g^5 .

When the box is to be folded, the fastening-pins $e^3 g^3$ have simply to be removed and the cover D and bottom D' drawn endwise from the flanges $a' a'$ of the side walls, a . This done, the body of the box may be collapsed into nearly a flat state, as shown in Fig. 4, the sides and ends turning on the hinges c .

In order to set up the box, the main body has simply to be aligned upon the hinges c and the bottom D' slid upon the flanges a' , so that the flanges d' clasp the flanges a' , as shown in Fig. 3, which firmly holds the bottom in place and causes the bottom to hold the main body from collapsing. The pins g^3 may now be inserted and the box filled. After this the cover D is to be slid in place to cause the flanges a' and d to clasp. The pins e^3 are then put in place, which locks the cover and also the entire box firmly in upright position, so that it and its contents can be safely shipped to any distance.

When the box is to be returned, the cover and bottom will be simply removed and the body collapsed and the whole shipped flat.

Having thus described my invention, what I claim as new, and desire to secure by Letters Patent, is—

1. As a new article of manufacture, a knock-down box having a main body composed of sheet-metal side pieces, $a a$, and sheet-metal end pieces, $b b'$, hinged together, and the top D and bottom D' , united to the edges of the said end and side walls, substantially as described.

2. The side wall, $a a$, formed with the edge flanges, a' , and hinged to the end walls, $b b'$, in combination with the top and bottom pieces,

D D', formed with the edge clasps or flanges, *d d'*, to engage with the flanges *a'*, substantially as described.

3. The end walls, *b b'*, hinged to the side walls, *a a*, the wall *b'* being formed with slots *g'*, in combination with the bottom D', formed with the flange *g* and provided with the fastening-lugs *g'* and fastening devices *g*, substantially as and for the purposes set forth. 20

4. The end walls, *b* and *b'*, hinged to the side walls, the wall *b'* being provided with the lugs *f*, in combination with the top D, formed with the flange *d*, formed with the slots *d*, and the fastening-pins *e*, substantially as and for the 25 purposes described.

5. The side walls, *a a*, and end walls, *b* and

b', the latter provided with permanent springs having fastening-pins, in combination with the cover D and bottom D', provided with flanges and fastening-lugs, substantially as described. 20

6. The body of the box, composed of the end walls, *b b'*, hinged to the side walls, *a*, the latter formed with the edge flanges, *a'*, and the end wall, *b'*, provided with fastening devices, in combination with cover and bottom formed 25 with edge flanges, *d d'*, and end flanges, *d' g*, and fastening-lugs upon the cover and bottom, substantially as and for the purposes set forth.

JOHN HOTHAM.
